SNAP ACTION DEVICE

Charles L. Martin, Overland, Mo., assignor to Carter Carburetor Corporation, St. Louis, Mo., a corporation of Delaware

Application March 23, 1944, Serial No. 527,855

3 Claims.

(Cl. 74—97)

This invention relates to snap action devices such as may be advantageously used to control a carburetor fuel cut-off valve.

Where a multiple cylinder internal combustion engine is run on part only of its cylinders during light load operation, as has been previously suggested, it is essential that the cut-off valve act quickly, in approaching and leaving its fully closed position, to prevent the supplying of an over lean mixture to the cylinders effected which may cause back firing and burn the valves. In the well known "Carter" carburetor, the main fuel jet or orifice is controlled by a metering pin which extends through the top of the fuel bowl and is operated by a pivoted lever connected to the throttle. Where this carburetor is used with certain multiple cylinder engines, particularly, where some of the cylinders are to be cut-out for light load running, separate barrels of the carburetor feed separate groups of cylinders. The metering pin may be conveniently used to cut off the main fuel supply to one barrel and the corresponding cylinder group. However, very little space is available for the installation of known types of snap action devices. Moreover, these devices have not been positive in their action and, usually, have been of relatively light construction.

Accordingly, an object of the present invention is to provide a snap action device which is compact and durable and can be conveniently applied to a carburetor metering pin controlling a group of cylinders which are cut in and out as the power requirements of the engine vary.

Another object is to provide a snap action device which positively limits the movement of the valve while, at the same time, insuring positive opening and closing thereof at the correct time.

Still another object is to provide a snap action device which permits continued movement of the prime mover element beyond the point where the snap action occurs, without continued movement of the valve.

These objects and other more detailed objects hereafter appearing are attained in the device illustrated in the accompanying drawings in which:

Fig. 1 is a diagrammatic view representing a multi-cylinder internal combustion engine with intake manifolding and a carburetor applied thereto.

Fig. 2 is a vertical section illustrating a carburetor for application to the above engine.

Fig. 3 is an enlarged detail view showing the

snap action mechanism just before tripping the valve open.

Fig. 4 is a top view of the structure in Fig. 3.

Fig. 5 is a view similar to Fig. 3, but showing the valve just after tripping open.

Fig. 6 is a view similar to Fig. 5 but showing the shifter at the extreme of its outward movement.

Fig. 7 is a similar view showing the valve just on the point of tripping closed.

Fig. 8 is a similar view showing the shifter at the extreme of its valve closing movement.

Fig. 1 shows an eight cylinder engine in which cylinders 1, 2, 7 and 8 are fed by a manifold branch 10 and cylinders 3, 4, 5 and 6 are fed by a separate manifold branch 11. At the centers of these manifold branches there is mounted a dual carburetor, generally indicated at 12, and better shown in Fig. 2.

The carburetor comprises float bowls 14 and 15 within which fuel is maintained at a substantially constant level by means of floats 16 and 17 and the usual needle valve mechanism (not shown). A pair of downdraft mixture barrels are shown at 18 and 19 having air inlets 20 and 21 controlled by a choker valve 22 pivoted on a shaft 23 which may be controlled by any suitable manual or automatic means. The valve is slit, as at 24 to accommodate a partition 25 which extends to the top of the carburetor so that suction applied to one barrel will not affect the other barrel.

Fuel is supplied to each barrel through main metering orifices 27 and 28 and upwardly inclined main nozzles 29 and 30 discharging into primary venturis 31 and 32. The discharge end of barrel 18, which supplies outer manifold 10, is controlled by a butterfly throttle valve 35 on a shaft 36 controlled by the usual linkage (not shown) extending to the accelerator pedal in the driver's compartment. The discharge end of barrel 19 is constantly open, no throttle being provided therein.

Metering orifice 27 is controlled by a metering pin 37 connected to a lever 38 pivoted above the top of bowl 14 and, in turn, connected by a link 39 to an arm 40 on throttle shaft 36. Metering pin 41, controlling metering orifice 28, is connected at its upper extremity to a U-shaped actuator 42, loosely pivoted on shaft 43 and comprising part of the snap action mechanism to be described hereafter. Pin 41 has a valve forming enlargement 46 for closing orifice 28. Shaft 43 is journaled in a stanchion 44 received between the legs of actuator 42 (Fig. 4).

Rigidly mounted on shaft 43 is a valve shifter lever 45 which extends in opposite directions from shaft 43. Valve actuator 42 has a pair of fingers 47 and 48 projecting from its outer arm 49. A pair of coiled springs 50 and 51 connect a pin 52 at the right hand end of shifter lever 45 (Fig. 3) and pins 53 and 54 at the extremities of fingers 47 and 48. A pin 55 projects inwardly from the opposite end of lever 45. The outer arm of the actuator also has a pair of slots 56 and 57 located just inwardly of fingers 47 and 48.

Inner arm 58 of the U-shaped actuator has a U-shaped lateral extension 59 which receives the upper extremity of metering pin 41 between enlargements 60 thereon for actuating the same 15 in both directions.

A pair of locking members 62 and 63 are pivoted on a common stub shaft 64 and constantly urged against the extremity of arm 49 of the actuator by the extremities 65 and 66 of a torsion 20 spring coiled about shaft 64.

The operation of the mechanism is as follows:

As the throttle valve is opened from the fully closed position of Fig. 2, to the fully open position, the snap action device moves progressively through the positions in Figs. 8, 3, 5, 6, and 7. Fig. 8 shows the shifter lever 45 fully rotated in the counterclockwise direction so as to move enlargement 46 on pin 41 against metering orifice 28 and thereby cut off the supply of fuel there-through. Shifter lever 45 can move clockwise to the position in Fig. 3 without affecting the metering pin, since locking member 62 remains lodged in slot 55 so as to prevent rotation of the actuator. During this movement, pin 55 at the left hand end of the shifter lever, moves against locking member 62 and, in Fig. 3, has lifted this lever just to the point of releasing the same from notch 57. In Fig. 5, locking member 62 has been released from locking engagement with the actuator, and the latter has been shifted clockwise, together with the metering pin 41, by upper tension spring 51, so as to quickly and fully open valve 46. Lower locking member 63 is immediately engaged in slot 56 so as to prevent further rotation of the actuator. However, the shifting lever 45 can continue its clockwise movement to the position in Fig. 6, in which upper spring 51 is further stretched. Throttle valve 35 will then be fully opened.

During closing of the throttle, shifting lever 45 moves counterclockwise to the position in Fig. 7, which shows spring 50 tensioned and member 63 just on the point of release from notch 56. In starting position in Fig. 8, locking member 63 has released the actuator, for snap movement in a counterclockwise direction by spring 50 so as to fully close valve 46, and upper locking member 62 is re-seated in notch 57.

The device, therefore, is positive in its action in both directions as to the extent of movement of the valve and as to the exact point during the throttle movement when shifting occurs. The valve is always either fully opened or fully closed so that there can be no period when an excessively lean mixture is supplied through barrel 19 to the inner group of cylinders. The device, further, is rugged, compact and simple of construction. Various modifications may be made as will occur to those skilled in the art and the exclusive use of all modifications as come within the scope of the appended claims is contemplated.

I claim:

1. A snap action device comprising an actuator element and a shifter element pivoted on a common shaft, spring means connecting said elements, and locking members pivoted on a common shaft eccentric of said first shaft and normally urged, one at a time, into locking engagement with said actuator element, said shifter element having a part movable between said locking members and disposed to engage the same, respectively, at spaced points in the shifter stroke, to release the same from said actuator and permit shifting of the latter by said spring means.

2. A snap action device comprising an actuator disk and a shifter lever pivoted on a common shaft, spring means resisting relative rotation between said disk and lever, said disk having notches at spaced points on its periphery, and locking detents normally urged against the edge of said disk and positioned to selectively enter said notches during the rotation of said disk to lock the same, said shifter lever having a projection disposed to selectively engage said locking detents near the ends of the normal stroke of said shifter to remove the same from locking relationship with said disk so as to release said disk for shifting by said spring means.

3. A snap action device comprising an actuator disk and a shifter lever pivoted on a common shaft, spring means between said disk and lever resisting relative movements in opposite directions thereof, a pair of locking detents having a common pivotal mounting eccentric of the pivot of said disk and lever, spring means normally urging said detents against the adjacent edge of said disk, said detents being disposed to selectively enter said notches at the ends of the normal stroke of said actuator, and said shifter lever having a projection between said detents positioned to selectively engage the same as said shifter approaches the ends of its stroke to withdraw the detent from locking relationship with said disk and thereby release said disk for movement by said spring means.

CHARLES L. MARTIN.
